United States Patent Office

Des. 178,615
Patented Aug. 28, 1956

178,615

TRAILER

Carl W. Ruegg, Raymond Grigsby, Ralph W. Starr, and
Donald G. Herzog, Selma, Calif.; said Grigsby and said
Starr assignors to said Ruegg and said Herzog

Application April 18, 1955, Serial No. 35,560

Term of patent 14 years

(Cl. D14—3)

FIG. 2.

FIG. 3.

Fig. 1 is a perspective view of a trailer showing our new design.

Fig. 2 is a side elevation of the trailer shown in Fig. 1, opposite sides of the trailer being of the same ornamental appearance.

Fig. 3 is a rear elevation of the trailer.

We claim:

The ornamental design for a trailer, as shown.
